W. P. HULBERT

SADDLE GIRTH

Filed Nov. 9, 1927

Inventor
William P. Hulbert

By *James L. Donohue*
Attorney

UNITED STATES PATENT OFFICE.

WILLIAM P. HULBERT, OF MIDDLEBURG, VIRGINIA.

SADDLE GIRTH.

Application filed November 9, 1927. Serial No. 232,066.

This invention relates to saddle girths and has for its chief object to produce a saddle girth to which the devices, such as buckles, whereby the ends of the girth are secured to the billets carried by the saddle are so attached to the girth that, when, after a horse has been saddled and ridden for a short distance, it becomes necessary to tighten the girth, only one of such securing devices need 10 be adjusted on its associated billet to properly tighten the girth.

A further object of the invention is to so construct a saddle girth that, when the billet-engaging devices carried by one end of the 15 girth are in engagement with the billets at one side of a saddle, the tension exerted by said billets upon their associated billet-engaging devices will be equally distributed between the latter.

20 The most satisfactory type of saddle girth is that which has at each end two or more billet-engaging devices, such as buckles, each pair of which devices is engageable with a pair of the billets carried by the saddle beneath a flap at one side of the saddle. But in using such a girth it is necessary that the buckles or other billet-engaging devices be secured to the billets at substantially equal distances from the points of attachment of 25 such billets to the saddle in order to secure a proper fit of the saddle, since if one of the billet-engaging devices engages its associated billet at a greater distance from the point of attachment of such billet to the saddle than 30 the other billet-engaging device engages its associated billet, unequal tension will be exerted upon the girth adjacent its opposite edges, which may permit the saddle to slightly shift on the back of the horse at 35 each movement of the horse and thus produce sores upon the back of the horse.

40 When a horse is first saddled he usually resists the tightening of the girth by expanding his diaphragm, and this makes it difficult, if not impossible, to draw the girth as 45 tight as it should be in order to secure a proper fit of the saddle. But after a short time it becomes possible to draw the girth tighter in order to more firmly secure the saddle in place and thus prevent it from 50 shifting. Accordingly, the rider usually, after riding a short time, attempts to draw the girth tighter without dismounting. This he does by lifting the flap at one side of 55 the saddle and pulling up first on one billet

and then upon the other in order to cause the billet-engaging devices which are connected to the girth to engage the billets at points nearer to the points of attachment of the billets to the saddle. But where the 60 horse is spirited or has become restive it is often difficult to adjust both billet-engaging devices on their associated billets and at the same time to keep the horse under control, so that frequently proper adjustment is made 65 of only one of the billet-engaging devices, with the result that unequal tension is exerted upon the girth adjacent the edges of the latter. These disadvantages are overcome by my invention.

70 The invention will be described with reference to the accompanying drawing, wherein:

75 Figure 1 is a perspective view of one side of a saddle having the girth of the present invention attached thereto, the side flap of the saddle being shown as raised to disclose the girth-securing devices; and

80 Figure 2 is a perspective view of a complete saddle girth embodying the invention.

85 Referring to the drawing in detail, 1 designates a saddle having the usual side flaps 2, which overlie the usual billet straps for engagement by the securing devices carried by the girth 5. In Figure 1 the saddle is shown as provided with two such billet straps 3 and 4 and the flap 2 is shown as raised to expose said straps.

90 Saddles are usually provided with two or more billet straps at each side thereof, as is contemplated in the present instance.

95 The girth of the present invention is provided, preferably at each end, with a pair of devices, here shown as buckles 6 and 7, for engagement, respectively, with the billet straps 3 and 4 of the saddle in order to attach the girth to the saddle and to provide means for tightening the girth. The buckles 6 and 7 are adjustable longitudinally of the billets 3 and 4, as by engagement with 100 the holes 8 in the latter. The buckles 6 and 7 are not connected directly with the girth as heretofore, but are carried by flexible means 11 which, in turn, is connected to the girth so as to permit movement of the 105 buckles relatively to one another and to the girth. Such flexible means is shown as a strap 11 which has its opposite ends 14-14' connected to each end of the girth adjacent 110 the opposite edges of the latter and which

extends and is slideable through the rear loops 9 and 10 of the buckles 6 and 7. The strap 11 also extends and is slideable through a loop 12 which is secured to the end of the 5 girth between the points of attachment of the ends of the strap thereto. In the present instance, the loop 12 is shown as rectangular in shape in order that the strap may slide freely through one end thereof 10 and as secured to the girth by means of a strap 13 passing through its rear end and stitched to the girth, as at 15.

In the construction just described, the buckles may be said to be floatably carried 15 by the girth, that is to say, if one of the buckles, for example, the buckle 6, is not in engagement with a billet, and a pull is exerted upon the other buckle 7, such pull will exert tension upon the strap which 20 will draw the strap 11 through the loop 12 and also through the rear loop 9 of the buckle 6. This will draw the buckle 6 toward the end of the girth. But if the buckles 6 and 7 are in engagement, respectively, 25 with the billets 3 and 4 and one of said buckles is moved upon its associated billet to engage the latter at a point closer to the point of attachment of such billet to the saddle, this will draw the strap 11 through 30 the loop 12 and also through the rear loop of the other buckle to permit such movement. In this way the tension exerted upon one of said buckles in tightening the girth will be transmitted to the other buckle and to 35 the billet engaged by the latter. Therefore, if the rider, after having saddled and mounted his horse, wishes to tighten the girth, he may lift the flap 2 and draw one of the billets 3 or 4 a greater distance through its asso- 40 ciated buckle 6 or 7 so as to cause said buckle to engage its associated buckle at a point closer to the saddle and thus cause the other buckle to exert greater tension on its associated billet. Thus the tension exerted 45 upon the girth by the billets 3 and 4 will be substantially equalized by adjusting one of the buckles on its associated billet without its being necessary to readjust the other buckle on its associated billet.

50 Although the girth has been shown as having each of its ends provided with billet-engaging means embodying the invention, it is obvious that the girth may have a pair of billet-engaging buckles secured 55 directly thereto in the ordinary way and be provided at the other end with the billet-engaging means of the invention.

While I have shown and described the 60 preferred embodiment of the invention, it is to be understood that such changes or variations may be made therein as come within the scope of the appended claims.

I claim:

65 1. The combination with a riding saddle having a plurality of billets, and a girth

having a plurality of buckles, one to each billet, of an equalizing means connected directly to and connecting all of the buckles to the girth, whereby when the respective buckles and billets are connected and any 70 pair of the respective buckles and billets are tightened, the strain therefrom will be equalized upon all of the buckles and billets.

2. The combination with a riding saddle and a girth, of a connecting medium between 75 the two, including a plurality of cooperating straps and buckles, and an equalizing means slidably connecting all of the buckles, whereby when all of the straps and buckles are connected and one strap is tightened, the 80 strain therefrom will be equalized between the girth and saddle between the straps and buckles.

3. The combination with a riding saddle and a girth, of a connecting medium between 85 the two, including two straps and two buckles, and a third strap slidably connected to said buckles and to the girth, whereby when all of the straps and buckles are connected and one strap is tightened, the 90 strain therefrom will be equalized upon all of the buckles.

4. The combination with a riding saddle and a girth, of a connecting medium between 95 the same, including two straps and two buckles, and a third strap having its terminals attached to either member to be connected, and having the two buckles strung thereupon between the terminals, whereby when all of the straps and buckles are connected and one strap is tightened, the strain 100 therefrom will be equalized through all of the buckles.

5. A saddle and girth connecting device, 105 including two straps, two buckles and a third strap, the buckles being strung on the third strap which forms a flexible attaching means for the buckles and having its ends fast to the opposite member to the two straps, whereby when all of the straps and buckles are connected and one strap is tightened, the strain 110 is equalized upon all of the buckles.

6. The combination with a saddle and 115 girth, of a connection between the two, including two billets carried by the saddle, two buckles, a strap having its two ends connected to the girth, and a loop attached to the girth between the strap ends, said strap being slidably mounted through the loop and also through the buckles, whereby when the buckles are engaged to the billets the tightening of either one of the billets produces a strain to be equalized through the 120 two billets, the loops, and buckles.

7. The combination with a saddle and 125 girth, of a connection between the two, including two billets carried by the saddle, two buckles, a strap having its two terminals connected to the girth and its interme- 130

diate portion strung through the buckles so that the buckles are slidably mounted thereon, and a loop attached to the girth between the terminals of the strap, said strap being 5 slidably mounted through the loop and the loop disposed between the buckles.

8. The combination with a saddle and girth, of a connection between the two, including two billets carried by the saddle, two 10 buckles, a strap having its two terminals connected in spaced relation to the girth, and a loop attached to the girth between the terminals of the strap, said strap being

threaded through one knuckle, the loop and the next buckle in the formation of a spiral, 15 whereby when either one of the billets is tightened respectively to one of its buckles the peculiar threading of the strap through the knuckles and loop will produce an equalization of pull upon the girth regardless of 20 the positions of the buckle upon which the adjusting strain is placed.

In testimony whereof I have hereunto set my hand.

WILLIAM P. HULBERT.
